UNITED STATES PATENT OFFICE.

HARRY D. GIBBS, OF SAN FRANCISCO, CALIFORNIA, AND COURTNEY CONOVER, OF PHILADELPHIA, PENNSYLVANIA.

PROCESS FOR THE MANUFACTURE OF PHTHALIC ANHYDRID, PHTHALIC ACID, BENZOIC ACID, AND NAPHTHAQUINONES.

1,284,888.

Specification of Letters Patent. Patented Nov. 12, 1918.

No Drawing.

Application filed May 12, 1917. Serial No. 168,216.

(DEDICATED TO THE PUBLIC.)

To all whom it may concern:

Be it known that we, HARRY D. GIBBS and COURTNEY CONOVER, citizens of the United States of America, residing in the city of San Francisco, county of San Francisco, State of California, and in the city of Philadelphia, county of Philadelphia, State of Pennsylvania, respectively, (whose post-office address is Washington, D. C.,) have invented a new and useful Process for the Manufacture of Phthalic Anhydrid, Phthalic Acid, Benzoic Acid, and Naphthaquinones.

This application is made under the act of March 3, 1883, chapter 143 (22 Stat., 625), and the invention herein described and claimed may be used by the Government of the United States or any of its officers or employees in the prosecution of work for the Government, or any person in the United States, without payment to us of any royalty.

Our invention relates to a process for the manufacture of phthalic anhydrid, phthalic acid, benzoic acid and naphthaquinones from naphthalene.

It is well known that phthalic anhydrid and phthalic acid are commonly produced by the oxidation of naphthalene by means of sulfuric acid in the presence of mercury sulfate and that naphthaquinones are produced by the oxidation of naphthalene by various oxidizing agents in liquid form and that benzoic acid is commonly produced from toluene. To manufacture phthalic anhydrid, phthalic acid, benzoic acid, and naphthaquinones by the methods commonly employed in general requires the employment of costly oxidizing reagents. In addition products obtained by these methods are frequently produced in forms which make them difficult to separate and purify. The object of our invention is to provide a process for the manufacture of the materials named which will be free from the objectionable features of the processes employed at present.

Our invention consists in the production of phthalic anhydrid, phthalic acid, benzoic acid and naphthaquinones from naphthalene by heating the naphthalene until it passes into the vapor phase, mixing this naphthalene vapor with an oxygen-containing gas mixture, forcing this mixture of gases into

close contact with finely divided oxids of molybdenum, heated to a temperature ranging from 250° C. to 650° C., under which treatment the naphthalene is oxidized to form the valuable products named, together with carbon dioxide and water.

To illustrate the practical operation of our process we shall describe in detail the preferred procedure. Naphthalene is melted and is caused to flow continuously at a measured rate into a heated chamber where it is volatilized. This vapor of naphthalene is then mixed with air in excess of the proportion theoretically required to oxidize naphthalene to phthalic anhydrid. The mixture of air and naphthalene vapor is passed into a reaction chamber maintained at a temperature ranging from 350° to 550° C., the preferred temperature being 500° C. This procedure produces the largest yields of phthalic anhydrid. In this chamber the gas mixture is forced into close contact with oxids of molybdenum in the form of a fine powder. This powder is supported on trays where, by means of baffle plates, the current of mixed gases is forced through it. The gases are kept under pressure only sufficient to cause them to flow continuously through the reaction chamber. The products of the reaction, consisting of phthalic anhydrid and other oxidation products of naphthalene, are condensed, together with unchanged naphthalene, by well-known processes. Phthalic anhydrid, together with small portions of other oxidation products, is separated from the unchanged naphthalene by fractional sublimation.

We have discovered that the process as above described may be varied in many ways and yet will produce one or all of the oxidation products named. Thus, oxygen may be substituted wholly or in part for air, or air may be mixed with a gas which is relatively inert under the conditions obtaining in the process. The oxids of molybdenum may be mixed with or combined with other substances, such as other metallic oxids, asbestos, pumice stone, or other inert materials. The gas mixture may be brought in contact with or forced through the catalyst in many different ways. The proportion of naphthalene vapor to the oxygen-containing gas mix-

ture may be varied within wide limits. And the reaction products may be separated by various well-known means differing from the fractional sublimation mentioned above. 5 Thus the acid constituents may be dissolved in alkaline solutions and subsequently freed from their salts by the addition of sulfuric or phosphoric acid and then sublimed. Or the reaction products may be treated with 10 ammonia gas or aqueous solutions of ammonia or various amines to produce other useful and valuable compounds.

Having thus described our invention we claim—

- 15 1. A process for the manufacture of phthalic anhydrid, phthalic acid, benzoic acid and naphthaquinones, which process consists in subjecting naphthalene in the gaseous state and mixed with an oxygen-containing gas mixture, to the action of molybdenum oxids heated to temperatures ranging from 350° to 550° centigrade.
- 20 2. A process for the manufacture of

phthalic anhydrid, phthalic acid, benzoic acid and naphthaquinones, which process 25 consists in subjecting naphthalene in the gaseous state and mixed with atmospheric air to the action of molybdenum oxids heated to temperatures ranging from 350° to 550° centigrade. 30

3. A process for the manufacture of phthalic anhydrid, phthalic acid, benzoic acid and naphthaquinones, which process 35 consists in subjecting naphthalene in the gaseous state and mixed with an oxygen-containing gas mixture, to the action of molybdenum oxids heated to temperatures ranging from 250° to 650° centigrade.

In testimony whereof we affix our signatures in the presence of two subscribing witnesses.

HARRY D. GIBBS.
COURTNEY CONOVER.
